CLAIM

The ornamental design for an automated transaction machine, as shown and described.

DESCRIPTION

FIG. 1 is a left-front perspective view of an automated transaction machine showing our new design.

FIG. 2 is a right-front perspective view of the automated transaction machine of FIG. 1.

FIG. 3 is a front view of the automated transaction machine of FIG. 1.

FIG. 4 is a back view of the automated transaction machine of FIG. 1.

FIG. 5 is a left side view of the automated transaction machine of FIG. 1.

FIG. 6 is a right side view of the automated transaction machine of FIG. 1.

FIG. 7 is a top view of the automated transaction machine of FIG. 1; and,

(Continued)

FIG. 8 is a bottom view of the automated transaction machine of FIG. 1.

The broken lines shown in the drawings represent portions of the automated transaction machine that form no part of the claimed design

1 Claim, 8 Drawing Sheets
